CLAIM

(21) Appl. No.: **29/120,317**

The ornamental design for a insert for child's seat, as shown and described.

(22) Filed: **Mar. 17, 2000**

DESCRIPTION

(30) **Foreign Application Priority Data**

FIG. 1 is a front view of an insert for child's seat according to my design;

Sep. 17, 1999 (DE) 4 99 08 598

FIG. 2 is a view from the right side of the insert for child's seat according to my design, the view from the left side being a mirror image thereof;

(51) LOC (7) Cl. **06-01**

FIG. 3 is a rear view of the insert for child's seat according to my design;

(52) U.S. Cl. **D6/333**

FIG. 4 is a perspective view from the top, front of the insert for child's seat according to my design;

(58) Field of Search D6/333, 500, 501,

FIG. 5 is a perspective view from the bottom, front of the insert for child's seat according to my design; and,

D6/502, 595, 596, 601, 610, 611; 5/655;

FIG. 6 is a view from the right side showing a possible environment for the invention in dash lines of the insert for child's seat according to my design in used position, the view from the left side being a mirror image thereof.

297/219.1, 219.12, 250.1

The dash lines included depict environment and are not part of the claimed design.
